UNITED STATES PATENT OFFICE

130,627

DESIGN FOR AN APRON

Vera F. Fulton, Gallipolis, Ohio

Application September 30, 1941, Serial No. 103,587

Term of patent 7 years

To all whom it may concern:

Be it known that I, Vera F. Fulton, a citizen of the United States, residing at Gallipolis, in the county of Gallia, and State of Ohio, have invented a new, original, and ornamental Design for an Apron, of which the following is a specification, reference being had therein to the accompanying drawing, forming part thereof, in which—

I claim:

The ornamental design for an apron, as shown.

VERA F. FULTON.
